SOLDERLESS WIRE CONNECTER

Robert A. Becker, Sr., and Stephen P. Becker,
Poughkeepsie, N. Y.

Application January 28, 1935, Serial No. 3,700

3 Claims. (Cl. 173—263)

This invention relates to a solderless-wire connector of that class which is intended to be employed for securing two or more wires together in a secure manner without the use of solder, and which may be used either above or below ground in making electrical connections and tapping feed wires or the like in electrical installations of all kinds.

The object of the present invention is to design a solderless-wire connector that shall be simple, contain few parts and those so designed that there shall be no loose parts to become lost or misplaced.

Another object of the invention being to construct a clamp which shall be durable, efficient and strong and provide a sure grip upon the wires.

Another object being to design a clamp that can be made from sheet metal to produce a cheap article for this purpose and especially for use with the smaller sizes of wires, and for use in service entrance connections.

Another object of the invention is to design a wire clamp in which a sliding member is employed to effect the gripping action on the wires, and is so arranged that it can not be removed from the body of the device.

With these and other objects in view, our invention consists in certain novel construction and combination of parts as will hereinafter be fully described and claimed, and further illustrated in the accompanying drawing which forms a part hereof and in which like figures of reference refer to corresponding parts in all of the views, and it is understood that slight changes may be made without departing from the spirit of the invention.

In the drawing:

Figure 1 is a front view of the clamp, showing the same as applied to two wires.

Figure 2 is a side view of the same.

Figure 3 is a vertical sectional view of the body member, or yoke.

Figure 4 is a side view of the clamping member.

Figure 5 shows the blank from which the body member is formed by a punch press operation.

Figure 6 is a vertical sectional view of the clamp showing the gripping action upon the wires.

Figure 7 shows a modified form of the clamp.

Figure 8 is a side view of the same.

Figure 9 is a vertical sectional view of the body member used in the form shown in Figure 7.

Figure 10 is an end view of this form of clamp.

Figure 11 shows the blank from which the body member is made.

Figure 12 shows a side view of the clamping member used in this construction.

Referring to the drawing:

While we have herein illustrated and described the clamp as being made from sheet metal stampings, we do not confine ourselves to this construction, as it may be desirable to employ castings for all or for a portion of the pieces.

In Figures 1 to 6 inclusive, we have shown our clamp as comprising a body or yoke member formed with a head 10 and the depending integral arms 11 of which are formed with the slots or openings 17 for the wires 16. The head 10 being thickened and having a transverse hole 14 which is threaded, for the locking screw 20.

The edges of the openings 17 in the arms 11 are formed with the flanges 12 for the purpose of increasing the width of the edges of said openings 17 and providing a larger supporting surface for the wires 16, and it is understood that this opening 17 may be of any desired shape and size, and thus the ends in place of being rounded may be V-shaped if desired.

The clamping member 13 is designed to be slidably mounted between the parallel arms 11 and it is also formed with an opening 19 of the same size and shape as the openings 17 in the body member and which is designed to register with these openings 17 when the clamping member 13 is in its reeded position, from which it is advanced or moved outward by the action of the screw 20 contacting with the upper end thereof.

This action produces a gripping action upon the wires 16, as shown in Figure 6.

For the purpose of guiding the movement of the clamping member within the arms 11 of the body member and to limit its outward movement and prevent its removal, the edges of the clamping member 13 are formed with the cut-out portions or notches 18, and the body member arms 11 are formed with the ears 15 which after the insertion of the clamping member 13 within the body member are bent inward or at right angles 45 to the arms 11 to lie within said notches 18 and providing stops for the movement of the clamping member 13.

In the modified form shown in Figures 7 to 12 inclusive, in place of the ears 15 being formed on the sides of the arms 11, and the edges of the clamping member 13 being provided with the notches 18, one or both sides of the clamping member 13 is formed with the grooves 22 extending from the lower edge to within a short dis-

tance of the upper edge, and one or both of the ends of the body yoke member 10 has formed on the end the ears 21, which when the article is assembled are bent at right angles to the arms 11 and engage with the grooves 22 to limit and guide the outward movement of said clamping member 13 within the body member 10.

While we have shown and described the two most effective ways for guiding and limiting the movement of the clamping member 13 within the body yoke, other means may be employed, such as knurling the inner faces of the arms 11 and the sides of the clamping member 13, or by a pin in one member entering a slot within the other member.

Also the opening 19 within the clamping member or block 13 may be open on the lower end, as this has no clamping action upon the wires 16, and it may be desirable to have this end open.

Further it may also be in some cases desirable to be able to insert the wires 16 from the side of the clamp in place of threading them through the openings 17 and 18, and this may be effected by providing both the body member arms 11 and the clamping member 13 with a cut out portion in one side through which the wires may be inserted.

The edges of the openings 17 of the body member arms 11 may be flanged on the outside as shown or upon the inner opposing faces, in which latter case, they may be employed as limiting guides for the clamping member 13.

Having thus described our invention, what we claim and desire to secure by Letters Patent, is:

1. In a solderless wire connector of the class described, the combination with a U-shaped open side body member comprising a head having two parallel integral arms spaced apart from each other and formed with oblong openings therein, a clamping member slidably mounted between said parallel arms and formed with a transverse opening therein, limiting and guiding means for said clamping member comprising parallel grooves formed on the sides for a portion of its

length and ears formed on the adjacent sides of said arms and projecting into said grooves, and a clamp screw threaded through said head and adapted to force the clamping member outward to grip wires passed through both the openings in the arms and in the clamping member.

2. In a device for clamping wires in contact with each other, the combination with an open-sided U-shaped member having a head and a pair of parallel integral arms formed with aligned wire receiving openings therein, a clamping member slidably mounted between said arms and formed with a wire receiving opening there-in and parallel guide grooves in the sides thereof upon the outer ends and closed on the inner ends, ears formed on one of the arms and projecting into said grooves to provide a stop for the movement of said clamping member with respect to the U-shaped member, and a screw threaded through said head and contacting with said clamping member to force the same away from the head and bring the openings in both the U-shaped member and the clamping member out of axial alignment to produce a clamping action upon the wires.

3. In a device for clamping wires in surface contact with each other, the combination with a U-shaped body member having a head and two depending parallel arms integral with the head and formed with aligned oblong openings therein, ears formed on said arms at right angles thereto, a clamping member slidably mounted between the arms and formed with a transverse opening and limiting guide grooves in the sides thereof open at one end and enclosed at the other end to form a stop for the reception of said ears, and a clamp screw threaded through said head in contact with said clamping member for forcing said members apart to clamp wires passed through the openings in both the arms and the clamping member.
